UNITED STATES PATENT OFFICE.

KENNETH SIMONDS JOHNSON, OF JERSEY CITY, NEW JERSEY, ASSIGNOR TO WESTERN ELECTRIC COMPANY, OF NEW YORK, N. Y., A CORPORATION OF ILLINOIS.

TELEPHONE SYSTEM.

1,162,069.

Specification of Letters Patent. Patented Nov. 30, 1915.

Application filed May 10, 1915. Serial No. 27,020.

To all whom it may concern:

Be it known that I, KENNETH SIMONDS JOHNSON, a citizen of the United States, residing at Jersey City, in the county of Hudson and State of New Jersey, have invented certain new and useful Improvements in Telephone Systems, of which the following is a full, clear, concise, and exact description.

10 This invention relates to telephone systems, and more particularly to substation circuits for such systems.

15 The object of this invention is to provide an improved and efficient telephone substation circuit by so combining certain of the necessary devices of a substation switching set that one or more may be made to serve a double purpose in the circuit, thereby eliminating certain devices which have here-
20 tofore been necessary.

25 In accordance with this invention, a substation circuit is provided with an electromagnetic signal receiving device, the usual transmitter and receiver, and switching means for inductively associating the receiver and the transmitter with a line circuit through the agency of the electromagnet of the signal receiving device.

30 For a more complete understanding of this invention, reference is made to the accompanying drawings showing one embodiment thereof and wherein—

35 Figure 1 is a diagram of a substation circuit with the apparatus therein in its normal position; that is, with the signal receiving device connected to receive signals; and Fig. 2 is a diagram of the substation circuit when the apparatus is connected in talking condition.

40 Referring to the drawings, 5 designates an electromagnetic signal receiving device having a U-shaped core 4. Windings 6, 7, 8 and 9 of the signal receiving device 5 are normally connected in series with line wires 10 and 11, through condenser 12 and switchhook contact 13. A transmitter 20 is in a normally open bridge of the line circuit, one terminal being connected to an intermediate point 21 of the windings of the elec-
45 tronagnetic device 5, and the other terminal being connected to a normally open switchhook contact 22. A receiver 23 is normally short-circuited by means of the switchhook contact 13. Switchhook 24 when

released by removing the receiver 23 there- 55 from, opens the short circuit from about the receiver 23 and serves to inductively connect the transmitter 20 and the receiver 23 with the line wires 10 and 11 through the windings 6, 7 and 8, 9 of the electromagnetic 60 signal receiving device 5, this condition of the substation circuit being shown in Fig. 2.

When the switchhook 24 is in its normal or depressed position as shown in Fig. 1, the circuit for signaling current (the source of 65 which is not shown) is from line wire 10, windings 6, 7, 8 and 9 in series, condenser 12 and switchhook contact 13 to line wire 11. When the switchhook 24 rises, upon the removal of the receiver 23, the open bridge 70 including the transmitter 20 is closed at switchhook contact 22, and the electromagnet of the signal receiving device 5, through its windings 6, 7 and 8, 9, acts as an induction coil serving to inductively associate the 75 transmitter and receiver with the line wires. When the receiver is off the switchhook, windings 6 and 7 are in series and form one winding of an induction coil, while windings 8 and 9 are in series forming the other wind- 80 ing of the induction coil.

Heretofore in telephone substation circuits employing induction coils, these induction coils have been separate and distinct from the signal receiving device. It will be seen 85 therefore that by utilizing the present invention, an efficient telephone substation circuit is obtained, and the cost of such circuits is materially reduced by the elimination of the separate induction coils. 90

What is claimed is:

1. In a telephone substation circuit, in combination, a line circuit, an electromagnetic device normally in circuit with said line to receive signals, a transmitter and a 95 receiver, and switching means for including said transmitter and said receiver in inductive relation to said line through the electromagnet of said device.

2. In a telephone substation circuit, in 100 combination, a line circuit, an electromagnetic device normally in circuit with said line to receive signals, a plurality of windings for said device, a transmitter in a nor- 105 mally open bridge of said line circuit and having one terminal connected to an intermediate point of said windings, a receiver, and switching means for closing said bridge

and for including said receiver in transformer relation to said line circuit through said windings.

3. In a telephone substation circuit, in combination, a line circuit, an electromagnetic device normally in circuit with said line to receive signals, a plurality of windings for said device, a transmitter and a receiver, and switching means for including said transmitter in series with one of said windings and said line and for simultaneously including said receiver and said line in inductive relation through said windings.

4. In a telephone substation circuit, in combination, a line circuit, an electromag-

netic device normally in circuit with said line to receive signals, a U-shaped core therefor, a plurality of windings on each leg of said core, a transmitter and a receiver, switching means and circuit connections 20 whereby upon the actuation of said switching means one winding of each leg forms a winding of an induction coil and another winding of each leg forms another winding thereof through which said transmitter and 25 said receiver are connected to said line.

In witness whereof I hereunto subscribe my name this 8th day of May, A. D. 1915.

KENNETH SIMONDS JOHNSON.
